UNITED STATES PATENT OFFICE.

CHARLES L. SULLIVAN AND WILLETT J. DICKINSON, OF CHICAGO, ILLINOIS; SAID DICKINSON ASSIGNOR TO HANDY CAR EQUIPMENT COMPANY, OF CHICAGO, ILLINOIS, A CORPORATION OF ILLINOIS.

BOLTLESS RAIL-SPICE.

No. 818,311.

Specification of Letters Patent.

Patented April 17, 1906.

Application filed January 27, 1906. Serial No. 298,162.

To all whom it may concern:

Be it known that we, CHARLES L. SULLIVAN and WILLETT J. DICKINSON, citizens of the United States, residing at Chicago, in the county of Cook and State of Illinois, have invented certain new and useful Improvements in Boltless Rail-Splices, of which the following is a specification.

Our invention relates to rail splices or joints used for connecting and holding in alinement ends of contiguous railway rails, and has for its objects; to provide a rail splice fastening in which greater security is provided in that a maximum intimacy of contact between the splices and the rails is insured and uninterruptedly maintained; to provide a rail splice fastening in which a secure holding is attained without the necessity of attention or manipulation being applied thereto, whereby a material reduction in what is known as maintenance charges is secured, and the liability of accident is reduced; to provide a rail joint splice which constitutes a perfect bond between the rails and makes the use of the present copper bonds unnecessary in electric railway service or where the rails are required to carry a current of electricity in block signal installation; to provide a positive means whereby the position of the splice bars relative to the ends of the rails will be maintained against the tendency of creeping or of movements due to contraction and expansion; to provide means whereby the looseness in the parts of the splice bars and rails due to wear is automatically taken up and the required tightness maintained; to provide a rail splice fastener that is adapted to engage the ties and act as an anti-creeper, and finally to provide a cheap rail splice fastener adapted to be attached to rails with the tools usually used by trackmen, and that can be substituted quickly and cheaply for the bolts now universally used with splice bars. The preferred forms of the invention are illustrated in the accompanying drawings, in which—

Figure 1 is a transverse section through the rail and splice bars, showing the securing means therefor;

Figure 2 is a similar section showing a modified form of spring;

Figure 3 is a similar section of another

modification in which means are provided for regulating the tension of the spring;

Figure 4 is a longitudinal section taken on the line (4) (4) of Figure 3;

Figure 5 is a side view showing the fasteners in position to act as anti-creeper devices, and

Figure 6 is a similar view of a modified arrangement.

As shown in Figure 1, 5 is the rail, and 6 are similar splice bars fitting against the inclined head and flange of the rail and spaced out from the web thereof so that when the 65 contacting surface is worn and the splice bars move inward, a secure engagement of splice bar and rail is still provided. 7 is the holding spring upcurved at its central portion 8 to contact with the bottom of the rail 70 and provided at its ends with portions 9 adapted to fit in the perforations in the splice bars and with collars 10 adapted to bear against the face of the splice bars and press the bars tightly against the rail. In order 75 to prevent the relative longitudinal movement of splice bars and rail the plug 11 is used, which plug engages each splice bar and also the web of the rail and is held in position by the parts 9 on the springs. It will be 80 understood that as many springs 7 may be used on the splice bars as is found necessary to hold the ends of the rails in proper position. These springs are necessarily constructed of very strong spring material, and 85 are sprung into position by means of the ordinary tools used by trackmen. The engagement of the parts 9 with the perforations in the splice bars secures the springs against lateral movement. It will be noted that the 90 springs provide an automatic means for taking up the looseness occasioned by wear caused by the rubbing of the faces of the splice bars and the rail together, and that after the spring is once in position the device 95 will require no further attention during the life of the rail. It will also be noted that the splice bars 6 are of ordinary construction and that the perforations therein are of the usual order, so that the applicants' device may be used to replace the ordinary bolts now used for holding splice bars, whereby the expense of substituting the applicants' construction in place of the ordinary one is slight. Atten-

tion is directed to applicants' provision of the central upturned portion of the spring which contacts with the bottom of the rail. This feature is of considerable importance, as the rail is made to act as a fulcrum and the effect thereof is that each half of the spring acts independently, and a stiffer spring is produced than if the spring were flat or straight along its bottom side. By virtue of this modification a smaller spring stock may be used than would otherwise be the case.

In Figure 2 a modification is indicated, which modification resides in the provision of collars 12 on the ends of the spring a short distance back from the collars 10. The object of this collar is to provide a means whereby a tool may conveniently engage the ends of the springs for forcing them apart. This feature adds greatly to the convenience in placing and detaching the springs. It will be apparent that any other engaging means on the springs might be used, as for instance a mere lug, or perhaps a hole through the springs stock.

In Figures 3 and 4, still another modification is shown. This modification resides in the means whereby the tension of the spring may be varied. This means consists in a wedge 13, which may be driven between the central portion 8 of the spring and the bottom of the rail. This wedge is shown in Figure 4, clearly, and as here shown is provided with notches 14 for holding the wedge in place after it has been driven in its desired distance. It will be apparent that other regulating means might be applied to the bottom of the spring, as for instance, set screws, or some other mechanical equivalent. It is also apparent that although stock for the spring is shown throughout the drawings as round some other section might be used without in any way departing from the spirit of the invention.

Figures 5 and 6 indicate how the device may be applied as an anti-creeper by virtue of the engagement of the bottom side of the fastener with the ties. When used in this way the fasteners are arranged obliquely as shown in order to apply their holding power more effectively in the direction of the length of the rail. It will be noted that part of the fasteners are obliqued in one direction and part in the other, the object being to hold the rail from longitudinal movement in both directions. When a wedge is used under the spring as shown in Figure 6 the top of the tie is cut away to accommodate such wedge.

Having thus described our invention and illustrated its use, what we claim as new, and desire to secure by Letters Patent, is the following:

1. In combination in a rail splice fastening, opposing splice bars having perforations, a spring passing beneath the rail and having its

ends bent upwards and inwards and entering the openings and provided with shoulders adjacent such ends adapted to bear against the faces of the splice bars.

2. In a rail splice fastening in combination, opposing splice bars having perforations, a spring passing beneath the rail with its center curved up to engage the bottom of the rail and having upwardly inturned ends entering the perforations and provided with shoulders adjacent such ends adapted to engage against the faces of the splice bars.

3. In a rail splice fastening in combination, opposing splice bars having perforations a spring passing beneath the rail with its center curved up to engage the bottom of the rail and having upwardly inturned ends entering the perforations and provided with shoulders adjacent such ends adapted to engage against the face of the splice bars, and means whereby the position of the curved up central portion of the spring relative to the bottom of the rail may be varied to adjust the tension of the spring.

4. In a rail splice fastening in combination, opposing splice bars having perforations, a spring passing beneath the rail with its center curved up to engage the bottom of the rail and having upwardly inturned ends entering the perforations and provided with shoulders adjacent such ends adapted to engage against the faces of the splice bars, and a wedge adapted to be forced between the bottom of the rail and the curved up portion of the spring.

5. In a rail splice fastening in combination, opposing splice bars having perforations, a spring passing beneath the rail with its center curved up to engage the bottom of the rail and having upwardly inturned ends entering the perforations and provided with shoulders adjacent such ends adapted to engage against the faces of the splice bars, and a wedge provided with a holding notch adapted to be forced between the bottom of the rail and the curved up portion of the spring.

6. In a rail splice fastening in combination, opposing splice bars, a spring having an upcurved center portion to engage the bottom of the rail and upcurved ends adapted to engage the splice bars, and means whereby the ends of the springs are held by the splice bars.

7. In a rail splice fastening in combination, opposing splice bars having alined perforations, a plug extending between the splice bars, a spring passing beneath the rail and having an upturned central portion engaging the rail and having upturned incurved ends adapted to fit the perforations and engage the splice bars to hold them against the rail.

8. In a rail splice fastening in combination, opposing splice bars having alined perforations, plugs extending between the splice bars, springs passing beneath the rail and having upturned central portions engaging

the rail and having upturned incurved ends adapted to fit the perforations and engage the splice bars to hold them against the rail, and means whereby the position of the upturned central portion of the spring may be adjusted relative to the bottom of the rail.

5 9. In a rail splice fastening in combination, opposing splice bars having perforations, a spring extending beneath the rail and having upwardly incurved ends engaging the perforations and engaging means for a removing tool on the spring adjacent its end.

10 10. In a rail splice fastening in combination, opposing splice bars, a spring extending beneath the rail and having upwardly incurved ends engaging the splice bars, and engaging means for an expanding tool on the spring adjacent its end.

15 11. In a rail splice fastening in combination, opposing splice bars with aligned perforations, a plug passing through a portion of each splice bar and the web of the rail, and a spring passing beneath the rail and having shouldered ends adapted to bear against the 20 splice bars and hold the plug in position.

25 12. A securing means for abutting rail ends, comprising splice bars overlapping the abutting rail ends, ties beneath the splice bars, and clamps adapted to hold the splice 30 bars and extending beneath the rail and engaging the ties to prevent creeping of the rails.

35 13. A securing means for abutting rail ends, comprising splice bars overlapping the abutting rail ends, ties beneath the splice bars, and obliquely directed clamps adapted 40 to hold the splice bars and extending be-

neath the rail and engaging the ties to prevent creeping of the rails.

45 14. A securing means for abutting rail ends, comprising splice bars overlapping the abutting rail ends, ties beneath the splice bars, and a plurality of clamps, a part of which are directed obliquely in one direction and the other part are obliquely directed in 45 the opposite direction adapted to hold the splice bars and extending beneath the rail and engaging the ties to prevent creeping of the rails.

50 15. A securing means for abutting perforated rail ends, comprising perforated splice bars overlapping the abutting rail ends, means extending through the perforations in the rails and splice bars to prevent relative longitudinal movement thereof, ties beneath 55 the splice bars and spring clamps engaging the perforations in the splice bars and extending beneath the rail and engaging the ties to prevent creeping of the rail in both directions.

50 60 16. In a rail splice fastening in combination, opposing perforated splice bars, a spring extending beneath the rail and having upwardly incurved shouldered ends engaging the perforations in the splice bars, and a collar on the spring adjacent the shoulder.

In testimony whereof we have hereunto signed our names in the presence of the two subscribed witnesses.
